DESIGN FOR AN ELECTRIC RANGE

Raymond E. Patten, Bridgeport, Conn., assignor
to Edison General Electric Appliance Company,
a corporation

Application April 27, 1934, Serial No. 51,543

Term of patent 14 years

To all whom it may concern:

Be it known that I, RAYMOND E. PATTEN, a citizen of the United States, residing at Bridgeport, in the county of Fairfield, State of Connecticut, have invented a new, original, and ornamental Design for an Electric Range, of which the following is a specification, reference being had to the accompanying drawing, forming a part thereof.

The accompanying drawing shows a perspective view of an electric range embodying my new design.

I claim:

The ornamental design for an electric range substantially as shown.

In witness whereof I have hereunto set my hand.

RAYMOND E. PATTEN,
